UNITED STATES PATENT OFFICE.

JOHN McDERMAID, OF ROCKFORD, ILLINOIS.

CLOSURE FOR CHURNS.

SPECIFICATION forming part of Letters Patent No. 399,681, dated March 19, 1889.

Application filed January 23, 1889. Serial No. 297,322. (No model.)

To all whom it may concern:

Be it known that I, JOHN McDERMAID, a citizen of the United States, residing at Rockford, in the county of Winnebago and State of Illinois, have invented a certain new and useful Improvement in Closures for Churns, of which the following is a specification.

This invention relates to an improved means of securing closures to churning; and it consists of certain new and useful constructions and combinations of parts hereinafter described, and pointed out in the claim.

Referring to the accompanying drawings, which form a part of this specification, Figure 1 is a plan view of a churn provided with my improvement. Fig. 2 is a view of a vertical section of the same through the dotted line $x x$ of Fig. 1. Fig. 3 is an isometric view of a portion of the churn-cover fastening shown in the foregoing views. Fig. 4 is an isometric view in detail of a fragment of the ring-head having a cover-guide lug projecting from its upper side. Fig. 5 is an isometric view of a cover-retaining lug.

Like letters of reference indicate corresponding parts throughout the several views.

A is a churn. A' is a ring-head seated in the croze A² therein.

A³ are cover-guide lugs projecting from the upper side of the ring-head A' along the chine of the churn A.

A⁴ is an annular bead projecting from the upper side of the ring-head A'.

B represents cover-retaining lugs projecting above the top of the churn A, whereto they are secured by means of spurs B', which enter the outside of the churn-staves, and bolts (not shown) passed through the bolt-holes B² therein and the staves of the churn.

C is a disk-head forming the basis of the churn-cover and having a vertical bolt-hole, C', through the center thereof.

C² is a metallic casing inclosing the periphery and upper peripheral angle of the disk-head C.

C³ is a transverse strengthening-brace integral with the casing C² and extending across the center of the disk-head C.

C⁴ is a vertical stud, also integral with the brace C³, and having a cylindrical passage, C⁵, extending longitudinally therethrough.

C⁶ is a ring of cork set into the disk-head C to engage with the annular bead A⁴, and forms a tight joint therewith.

D represents bails for securing the cover to the ring-head A', mounted in the cover-retaining lugs B by inserting the ends of the former through the holes B³ in the latter. These bails may be swung outward and inward, as indicated by the dotted lines x' of Fig. 1, according as it is desired to open or close the churn.

E is a bolt passed through the openings C' C⁵ in the disk-head and vertical stud, and is secured in position by means of the set-nut E'.

F is a fulcrum having a threaded passage, F', extending vertically therethrough to adapt it to engage with the threaded portion of the bolt E to form a vertical and adjustable swivel-joint therewith for the former to revolve upon.

G is a lever-cam consisting of the cam G', pivoted to the swiveled fulcrum F by means of the horizontal pivot G² and openings G³ in the cam G', and the lever G⁴, integral therewith, for operating the same. The cam G' is divided by a horizontal cleft, G⁵, therein, which admits the fulcrum F, whereto it is pivoted, and embraces the set-nut E', thereby preventing said nut from working loose and serving as a wrench to remove and replace the same when desired.

G⁶ is a cork stop inserted into a suitable socket on the under side of the lever G⁴ to prevent the latter from marring the disk-head C. To take up the slack between the bails and cam or the wear of any of the parts composing the fastening mechanism, elevate the lever to a vertical position and revolve it and the fulcrum whereto it is swiveled upon the bolt E, as indicated by the dotted circle x^2 in Fig. 1, until the slack or wear is taken up.

The cover-guide lugs A³ will be found to be highly useful for guiding the cover onto the churn in such a manner that only the middle portion of the lower surface of the ring of the cork C⁶ can come in contact with the annular bead A⁴ of the ring-head A', as a liquid-tight joint between the cover and churn is thereby positively assured—a condition attained with difficulty when the ring of cork is placed upon the bead of the ring-head in such a manner as not to be concentric therewith.

I claim—

In combination, a churn having cover-retaining lugs secured to the outside of and projecting above the chine of the same, a ring-head set into the chine thereof and having cover-guide lugs extending from the top of the latter along said chine, a cover fitted to

the chine-ring, and suitable fastenings for retaining said cover thereon, substantially as described, and for the purpose specified.

JOHN McDERRIDA.
